UNITED STATES PATENT OFFICE.

CECILIA C. CLANCY, OF CHICAGO, ILLINOIS.

DESIGN FOR A SEWING-THIMBLE.

SPECIFICATION forming part of Design No. 31,520, dated September 19, 1899.

Application filed August 26, 1899. Serial No. 728,631. Term of patent 14 years.

To all whom it may concern:

Be it known that I, CECILIA C. CLANCY, a citizen of the United States, residing at Chicago, in the county of Cook and State of Illinois, have invented a new and original Design for Sewing-Thimbles, of which the following is a specification, reference being had to the accompanying drawings, forming a part thereof, in which—

10 Figures 1 and 2 are side elevations of the thimble, but viewed from points each removed ninety degrees from the other.

As shown in the drawings, the leading or material feature of my design consists of a body portion substantially in the form of a truncated cone, but having its top rounded or convex. The upper portion of this body and also the end or dome are freely indented, and across the lower end there is a 15 band in relief. An aperture is cut transversely through the conical wall at a point slightly below its juncture with the convex or dome-shaped end, this aperture extending substantially half-way through the body portion, giving the thimble when viewed from a point opposite one end of this slot the appearance of a body portion surmounted by a canopy, supported at one side by a prolongation of the body.

Having thus described my invention, what I claim as new, and desire to secure by Letters Patent, is—

The design for a sewing-thimble as herein shown and described.

In testimony whereof I have signed my name to this specification in the presence of two subscribing witnesses.

CECILIA C. CLANCY.
